ABSTRACT: A low profile power relay contact is made possible by an assembly comprising a bifurcated contact spring having one shank bent above a level of the spring and overlapping an unbent shank whereby the bifurcated portions securely grip but do not impart rotative forces to an operating member which is moved up and down in response to movement of an armature by an electromagnetic field. A first carrier plate lies in generally the same plane as the unbent portion of the contact spring and is below the bent contact spring while a second carrier plate is bent to lie above the unbent carrier spring whereby upon movement of the operating member a contact is made and a contact is broken.

SWITCH-OVER CONTACT ARRANGEMENT FOR POWER RELAYS

BACKGROUND OF THE INVENTION

1. Field of the Invention

This invention relates generally to power relays and more particularly to a switch-over contact arrangement which will make possible the construction of power relays of a compact size.

2. Prior Art

General constructions according to the prior art include stacked contact-spring sets lying one above the other. In such constructions the minimum possible physical dimensions of a contact-spring set in insulating interlayers are, from a practical viewpoint, firmly established. Likewise, the contact spacings which are necessary in actual practice to provide voltage stability may not go below a certain minimum measurement. With these design factors substantially fixed it has heretofore not been possible in power relays to reduce the relay height below that permitted by these relatively fixed dimensions.

Because of the great press for the miniaturization of electrical and electronic components the power relays constructed according to the prior art have in effect become too large with respect to the other components whereby a great need has arisen for their reduction in size. Moreover, the increasing cost and complexity of electrical systems and their increasing costs of manufacture have made efficiency of design and manufacture a highly critical factor in their use.

SUMMARY OF THE INVENTION

The disadvantages of the prior art are overcome by the very efficient, convenient and economic structure of the present invention wherein a low profile switch-over contact arrangement for power relays comprises a contact spring of a generally planar configuration having a first end bifurcated to provide juxtaposed first and second spring leg portions each having one end connected to said contact spring and a free end portion with contact means thereon. The first leg has its free end portion bent out of the plane of the contact spring while the second leg remains generally in the plane of the contact spring. First and second carrier plates electrically insulated from said contact spring have an anchored end and a contact means carrying end with the means carrying the end of the first carrier plate lying below said first spring leg and the second carrier plate having its contact means carrying end bent out of the plane of the remainder of the second carrier plate and lying above the second spring leg portion.

We have found that by bending the portions of the legs and carrier plates we may place the contact springs and first and second carrier plates generally in the same plane and thereby assure a minimum overall height and a low profile.

A power relay plug-in base supports the contact spring, the carrier plate, an electromagnetic coil, a yoke, a yoke support, an armature stop and suitable connector prongs. A protective cover may be attached to the body by suitable means such as a clip. In practice we have found it advantageous to make the body member of a one-piece molded construction and to anchor the contact spring and the inner ends of the carrier plates directly into the body.

The free ends of the first and second leg portions are biased toward each other and securely grip the base portion of a U-shaped operating member which passes below the free end portion of the first leg and above the free end portion of the second leg. It is an important feature of this invention that the free end portions of the spring legs have laterally projecting portions which extend towards each other in their respective planes so that the laterally projecting portion of the first leg lies above the laterally projecting portion of the second leg. By means of this construction the rotative forces which would be applied to the operating arm by the spring legs are substantially diminished.

Upstanding arms at each end of the base portion pass through holes in the base portion of a U-shaped armature. In the illustrated embodiment the U-shaped armature partially encircles one end of an electromagnetic coil with the free ends 5 of the armature arms being connected to a spring-biasing means which acts to pivot the armature about the arm free ends and bias the armature base end upwardly against a stop member. The armature base end is also biased upwardly by 10 the second leg of the contact spring working through the operating arm. In this position the second spring leg free end portion contacts the bent portion of the second carrier plate to make electrical contact whereas the first spring leg free end portion will not be contacting the first carrier-plate portion. 15 When the coil is energized the electromagnetic field will drive the base portion of the armature toward the yoke and thus move the operating member downwardly in a direction generally perpendicular to the contact spring and the carrier plate whereby the second contact is broken and the first contact 20 between the first spring leg portion and the first carrier plate is made.

The free end portion of the first spring leg has a hole therethrough which receives an upstanding projection on the operating member. In this very simple manner the operating 25 member is held in position between the spring legs.

From the above brief summary the advantages of the present invention over the prior art may be clearly seen. Many other advantages, features and additional objects of the present invention will become manifest to those versed in the art upon making reference to the detail description and the accompanying sheets of drawings in which preferred structural embodiments incorporating the principles of the present invention are shown by way of illustrative example.

BRIEF DESCRIPTION OF THE DRAWINGS

FIG. 1 is an elevational side view with parts in cross section and with the side portion of the cover removed to illustrate a low profile power relay device embodying the present invention;

FIG. 2 is an elevational end view as the structure of FIG. 1 would be seen in a section along the lines II-II;

FIG. 3 is an enlarged perspective view of the details of the contact arrangement with parts broken away;

FIG. 3a is plan view of just the bifurcated end portion of the contact spring illustrating the overlap of the portions thereof;

FIG. 3b is an end elevational view of the structure of FIG. 3a again illustrating the overlap portions of the contact spring legs.

DESCRIPTION OF THE PREFERRED EMBODIMENT

Referring to FIG. 1 the low profile construction embodying the present invention may be clearly seen. A body 1 may be molded of insulating material and may be attached to a plug-in base B to support the component elements of the power relay. In practice we have found it convenient to mold the body 1 integrally with the base B so that insulating and structural integrity is assured. Moreover, this integral construction provides greater manufacturing and assembly economies. A protective cover A may be attached to the body 1 by any convenient means such as for example a clip 1a. Other body portions which may be separately or integrally formed include an armature stop 1b and a yoke support 1c as will hereinafter be described in greater detail.

A first carrier plate 2a may be best seen in FIG. 3 where it is shown projecting from the molded insulating body 1. The first carrier plate is of an L-shaped configuration having a first end 2aa anchored in the insulating body 1 and a second end 2ab projecting inwardly generally toward a centerline of the body and supporting a contact means 3 on its upper surface. A second carrier plate 2b also may be generally L-shaped having a first end 2ba anchored in the insulating body 1 and second end 2bb being bent out of the plane of the remainder for the 70 second carrier plate 2b and carrying a contact means 4 on its

lower surface. The distance which the second carrier plate portion 2bb is bent out of the plane of the remainder of the plate 2b is represented by the reference symbol a as shown in FIG. 3. Each of the anchored ends of the carrier plates is suitably connected into the electrical circuits in which the power relay operates.

A contact spring member 5 is supported in a usual manner on the body 1 and has its free end bifurcated by means of a slot in the free end to provide juxtaposed first spring leg portion 5a and second spring leg portion 5b. The first spring leg portion 5a has a free end portion 5ab bent out of the plane of the contact spring 5 by means of portion 5aa. A contact means 6 is provided in the undersurface of the free end portion 5ab. A laterally projecting portion 5ac is integral with the free end portion 5ab and extends towards and over a similar portion of the second contact spring leg 5b. The second contact spring leg portion 5b is generally in the plane of the contact spring 5 and has an outer free end 5ba from which there extends a laterally projecting portion 5bb. The portion 5bb underlies the laterally extending portion 5ac. A contact means 7 is supported on the leg 5b at a position below the contact means 4 on the second carrier plate.

An examination of FIGS. 3a and 3b clearly shows the overlapping of the laterally projecting portions 5ac and 5bb. A distance b represents the overlap which will vary in individual constructions depending on the differences in forces f_2 and f_1 in the spring legs 5a and 5b, respectively. In the area of overlap these forces operate against one another and are thereby substantially neutralized. The portion 5bb may extend a distance equal to or less than the width of a slot 5c and the length of portion 5aa may be greater than the length of 5ac or 5bb so that the portions 5ac and 5bb may be integrally formed without waste of any spring material.

An operating member 8 having a U-shaped configuration when seen in elevation has a base portion 8a underlying the first contact spring leg free end portion 5ab laterally projecting portion 5ac and overlying the free end portion 5ba and laterally extending portion 5bb of the spring leg 5b. The first spring leg free end portion 5ab has a hole 5ad therethrough which receives therethrough a projection 8d upstanding from the base portion of the operating member 8. The first and second legs 5a 5b are biased in a vertical direction towards one another so that their free ends hold the operating member base 8a in a pincerlike manner to grip it securely against movement. By means of the overlapping construction the rotative forces of the legs 5a and 5b which would tend to rotate the operating member 8 in a counterclockwise manner because of the spring bias of the legs is counteracted and substantially diminished to the point where it has no effect on the operation of the power relay. As may be seen in FIG. 2 a cutout portion 8aa acts to further limit any lateral movement of the first leg or the operating member 8. A second cutout 8ab is provided to allow access to the second contact shown by contact means 4 and 7.

Upstanding arms 8b and 8c at each end of the base portion 8a pass through holes 9b and 9c respectively in the base portion 9a of the a U-shaped armature 9. Widened portions 8bb and 8cb are provided in support of the operating member for the armature. Arms 9d and 9e extend from each end of the armature base 9a to partially encircle one end of an electromagnetic coil 11. The free ends of the armature arms 9d and 9e are connected to a spring-biasing means 9f which acts to pivot the armature about the arm free ends and bias the armature base end upwardly against the stop member 1b. In practice we have found a prestressed bearing spring 9f attached at one end to the free end of the armature end 9e and connected at the other end to a yoke 10 by a means 9g to provide excellent service and convenience of manufacture. A similar spring-biasing means (not shown) is provided for the other armature arm 9d. The armature base end is also biased upwardly by the second leg 5b of the contact spring 5 working through the operating arm 8. The yoke 10 is centrally positioned with respect to the coil 11 by the body 1 in the forward yoke support 1c.

OPERATION

Further advantageous features will be readily evident from a brief discussion of the operation of the power relay constructed according to the present invention. In a rest position as may be seen in FIG. 2 the coil 11 is not energized and the force in the second spring leg 5b together with the force in the bearing spring 9f bias the operating member 8 and the associated armature 9 upwardly against the armature stop member 1b. In this position the second spring leg free end portion 5ba with its associated contact means 7 rests against the contact 4 of the second carrier plate 2b. Contact means 4 and 7 complete what might be termed the second contact.

When the coil 11 is energized the accompanying magnetic field is concentrated in the soft iron yoke 10 which in turn pulls the armature 9 into contact therewith to overcome the force in the contact spring leg 5b and the bearing spring 9f. When the armature 9 pivots about the free end of the arms 9d and 9e it moves the operating arm 8 downwardly and this in turn pushes the spring leg 5b in its contact means 7 away from the contact means 4 to break the second contact. At the same time as the operating arm 8 moves down, the spring force in the free end portion 5ab of the spring leg 5 moves the contact means 6 secured thereto into contacting engagement with the contact means 3 on the first carrier plate 2a so that the first contact is made. Since the switch-over contact spring 5 lies operatively on voltage with its two spring legs 5a and 5b, there arises in their operative deflection, an electrical switch-over of the currents.

An important structural advantage attained by the bifurcation of the contact spring 5 is that a greater spring force may be provided in the first spring leg than in the second. Whereas the spring constants in known contact-spring sets are equal, this is not the case in the contact arrangement according to the invention because of the bending of one of the spring legs. Thus, the bend allows a specified spring force represented by f_2 to be imparted to the first leg whereas the second leg will carry the spring force of the contact spring 5.

From the above-noted summary and description of our invention it may be seen that we have provided a convenient, efficient and extremely economical compact power relay device that has many advantages over the prior art. A very low profile is provided by the arrangement of the carrier plates and contact legs on substantially the same level. This moreover allows a very short stroke. The simplicity of the construction lends itself to automation in manufacture and low maintenance in use. Any readjustments frequently required in known contact arrangements after assembly are dispensed with by the supporting of the movable parts on corresponding molded pieces.

Although minor modifications might be suggested by those versed in the art, it should be understood that we wish to embody within the scope of the patent warranted hereon all such embodiments as reasonably and properly come within the scope of our contribution to the art.

55 We claim:

1. A compact electrical contact arrangement comprising a generally planar single unitary contact spring having a movable free end, said contact spring being slotted at its free end to form adjacent first and second legs, said first leg having a free end bent out of the plane of the contact spring and said second leg having its free end generally in the plane of said contact spring, first and second carrier plates electrically insulated from said contact spring and each having a contact means carrying end, said contact means carrying end of said first carrier plate lying below said first spring leg and said second carrier plate having its contact means carrying end bent out of the plane of said corner plate and lying above said second spring leg portion said contact spring and said carrier plates lying in substantially the same plane.

60 2. An electrical contact arrangement according to claim 1 wherein said first spring leg has a greater spring force than said second spring leg.

65 3. A contact arrangement according to claim 1 wherein said contact spring and said carrier plates are anchored in a common body of insulating material.
